(57) **CLAIM**

The ornamental design for night vision goggles as shown and described.

DESCRIPTION

FIG. 1 is a front perspective view of night vision goggles showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is an enlarged detail view taken from portion 9 of FIG. 1;

FIG. 10 is an enlarged detail view taken from portion 10 of FIG. 2;

FIG. 11 is an enlarged detail view taken from portion 11 of FIG. 2;

FIG. 12 is an enlarged detail view taken from portion 12 of FIG. 3;

FIG. 13 is an enlarged detail view taken from portion 13 of FIG. 4;

FIG. 14 is an enlarged detail view taken from portion 14 of FIG. 5; and,

FIG. 15 is an enlarged detail view taken from portion 15 of FIG. 6.

Broken lines are used to depict portions of the night vision goggles in FIGS. 3 and 8 and to indicate enlarged portions in FIGS. 1-6 and 9-15. All broken lines form no part of the claimed design.
